UNITED STATES PATENT OFFICE.

WILLIAM VAN HORN, OF PIQUA, OHIO.

WEATHER-STRIP.

No. 800,343.

Specification of Letters Patent.

Patented Sept. 26, 1905.

Application filed December 9, 1904. Serial No. 236,220.

To all whom it may concern:

Be it known that I, WILLIAM VAN HORN, a citizen of the United States, residing at Piqua, in the county of Miami and State of Ohio, have 5 invented certain new and useful Improvements in Weather-Strips, of which the following is a specification.

This invention consists of a novel construction of metallic weather-strip.

10 The invention aims to provide a device of this type which may be readily applied to a window or like part without necessitating the use of special fastenings for this purpose and which is of a form effective as a cushion for 15 the window with which it coöperates and positively excluding all dust, rain, or like foreign matter.

The weather-strip comprising the invention embodies, essentially, a base mounted in the 20 runway of the window-sash and of substantially the width of such runway in order that it may be held in place by the adjacent parting or stop strips, the body of the strip being projected from the base and received by the 25 sash, as before premised.

For a full description of the invention and the merits thereof and also to acquire a knowledge of the details of construction of the means for effecting the result reference 30 is to be had to the following description and accompanying drawings.

While the invention may be adapted to different forms and conditions by changes in the structure and minor details without departing 35 from the spirit or essential features thereof, still some of the preferred embodiments are shown in the accompanying drawings, in which—

Figure 1 is a horizontal sectional view 40 showing the jamb of a window, sashes mounted therein, and weather-strips of a type embodying the invention in operative position. Fig. 2 is a broken perspective view of one form of weather-strip. Fig. 3 is a horizontal sectional view showing a slight modification of the construction shown in Fig. 2. Fig. 4 is a perspective view of the modification. Figs. 5 and 45 6 are sectional views of other modifications.

Corresponding and like parts are referred 50 to in the following description and indicated in all the views of the drawings by the same reference characters.

In its adaptation as shown the invention is applied to a window, the jamb of which is indicated at 1, the sash 2, the latter being

mounted for movement between the usual parting-strip 3 and stop 4. The weather-strips are mounted in the runway of the window and comprise, essentially, a base 5, from which extends the body of the weather-strip, 60 said body being received in a recess or slot 6, provided in a side of the sash 2 adjacent. The weather-strip is held in place by means of the parts 3 and 4, and special fastenings for these members are not utilized, being unnecessary. 65 The sides of the parting-strip 3 and the adjacent sides of the stops 4 are each provided with vertical grooves 7, which receive the edge portions of the base 5 of each of the weather-strips, thereby firmly holding the 70 weather-strip in its proper position in the runway of each sash. (See Fig. 1 of the drawings.) The base 5 is of course wider than the runway of the sash in order that its edge portions may be projected into the 75 grooves 7 for the purpose above mentioned.

The body of the weather-strip is peculiarly formed, being made by folding one of the edge portions of the base 5 upon said base, as shown at 8, the folded portion 8 being then 80 bent outwardly, as shown at 9, to form a side of the body of the strip. Spaced from the side 9 of the body of the strip is an adjacent side 10, formed by folding an edge portion of the side 9 upon itself. The foregoing general 85 structure of the weather-strip is common to all the modifications illustrated in the drawings. In the preferred form of the invention (shown in the construction of the strip to the left in Fig. 1) the side 10 of the body 90 is provided with a lateral flange 11, projected into the space between the base 5 and the portion 8, folded thereupon. The above structure is compact and substantial, being very desirable for use upon heavy windows, 95 wherein greater resistance to the rattling movement of the window is necessary. The construction in Fig. 3 is substantially the same as that at the left in Fig. 1. The side 9 of the body of the strip, however, projects 100 at an obtuse angle to the portion 8 aforesaid.

The modification shown at the right in Fig. 1 and in perspective in Fig. 4 is slightly different from the constructions before mentioned, the side 10 of the body of the strip 105 being bent in an opposite direction when folded upon the side 9 and having a laterally-projected flange 11^a, which is situated adjacent the upper side of the folded portion 8 of the base 5. The body portion of the strip in this 110

construction projects about at an obtuse angle to the base 5 and subserves the cushioning effect of the device.

In Fig. 5 the flange 11 (shown in the constructions at the left of Fig. 1 and in Fig. 2) is omitted from the body of the strip, this being the only essential difference. The side 10 of the device shown in Fig. 5 has free spring movement toward and from the side 9 to take up motion of the window, as will be readily apparent. The device illustrated in Fig. 6 is similar to the construction of the strip shown in Fig. 4, the only difference being also the omission of the flange 11^a. Where the window-sash have comparatively no lateral play, the spaced relation of the base 5 and the portion 8 thereof is sufficient to take up such play. In other instances it is desirable that the flange 11^a be used and that a double spring action of the parts is secured by movement of the portion 8 toward the base 5 and the flange 11^a toward said portion 8.

The base 5 is integrally formed with the body of the strip, the latter being bent from an edge portion of said base, as described more fully hereinbefore.

The strip is of comparatively simple formation and is readily removable by taking the window-stops 4 off of the jamb or frame 30 of the window, the strips coming off when the sashes 2 are displaced. The operation of placing the weather-strips in place is equally simple, as is obvious.

Having thus described the invention, what is claimed as new is—

1. In combination, a window-jamb, spaced strips applied to said jamb and forming a runway, a sash mounted in said runway and

having a slot in a side thereof, and a weather-strip comprising a base disposed in the runway and having its opposite edge portions engaged by the spaced strips aforesaid, one edge portion of the base being folded thereon and then projected outwardly to form a body portion, the outwardly-projected body portion being received in the slot of the sash aforesaid.

2. In combination, a window-jamb, spaced strips applied to said jamb forming a runway, a sash mounted in said runway, and a weather-strip comprising a base secured in the runway of the sash and coöperating with the spaced strips aforesaid, an edge portion of the base being folded thereon and bent outwardly to form a side of the body of the strip, 55 said side being refolded to form a spaced side.

3. A weather-strip comprising a base having an edge portion thereof folded upon itself, the folded portion of the base being projected outwardly therefrom to form a side, said side 60 being bent upon itself to form a second side in spaced relation thereto.

4. A weather-strip comprising a base having an edge portion thereof folded thereon, the folded portion of the base being projected 65 outwardly therefrom to form a side, said side being bent upon itself to form a second side in spaced relation thereto, and a flange extending from the last-mentioned side.

In testimony whereof I affix my signature in 70 presence of two witnesses.

WILLIAM VAN HORN. [L. s.]
